[57] CLAIM

The ornamental design for a combined bottle and stopper, substantially as shown and described.

DESCRIPTION

FIG. 1 is a side elevational view of a combined bottle and stopper showing my new design;
 FIG. 2 is an elevational view looking from the right of FIG. 1;
 FIG. 3 is an elevational view looking from the left of FIG. 1;
 FIG. 4 is a top plan view; and
 FIG. 5 is a bottom plan view.
 The side opposite that seen in FIG. 1 is a mirror image of the side shown.

FIG. 1

FIG. 2

FIG. 3

FIG. 4
